UNITED STATES PATENT OFFICE

HARRIETTE IRONS, OF OAK PARK, ILLINOIS

DESIGN FOR A CHEMISE

Application filed February 14, 1930. Serial No. 34,544. Term of patent 3½ years.

To all whom it may concern:

Be it known that I, HARRIETTE IRONS, a citizen of the United States, residing at Oak Park, in the county of Cook and State of Illinois, whose post-office address is 1032 S. Scoville Avenue, Oak Park, Illinois, has invented a certain new, original, and ornamental Design for Chemise, of which the following is a specification, reference being had to the accompanying drawing, forming a part thereof.

The figure of the drawing shows a front view of the chemise constituting my design, the detailed illustration of the left side front being continued on the right side front as indicated by the dotted line as well as about the entire back.

I claim:

The ornamental design for a chemise as shown and described.

Signed at Chicago, county of Cook, State of Illinois, this 12th day of February, A. D. 1930.

HARRIETTE IRONS.
